UNITED STATES PATENT OFFICE.

GEORGE W. TRAPHAGAN, OF GLENS FALLS, NEW YORK, ASSIGNOR TO
HIMSELF AND A. M. DECKER, OF THE SAME PLACE.

IMPROVEMENT IN SLAT-IRONS FOR CARRIAGE-TOPS.

Specification forming part of Letters Patent No. **59,322**, dated October 30, 1866.

To all whom it may concern:

Be it known that I, GEORGE W. TRAPHAGAN, of Glens Falls, in the county of Warren and State of New York, have invented a new and useful Improvement in Slat-Irons for Top-Carriages; and I do hereby declare that the following is a full, clear, and exact description thereof, which will enable others skilled in the art to make and use the same, reference being had to the accompanying drawings, forming part of this specification, in which—

Figure 1 is a side view of the lower end of a set of carriage-top bows with my improvement attached. Fig. 2 is an edge view of the same partly in section to show the construction.

Similar letters of reference indicate like parts.

My invention has for its object to so improve the construction of slat-irons for carriage-tops that the work of covering the bows may be done by machine instead of by hand, as the work is now done; and it consists, first, in attaching the bows to the fingers or hinge by screws; and, second, in the combination of the straps and finger-irons with each other, with the bows, and with the supporting-iron or rail, when the said straps and finger-irons are constructed substantially as herein-after more fully described.

A are the straps which are attached to the ends of the bows B. The upper parts, a^1 , of the straps A are made in the form of a half-round tapering strap, and they are secured to the ends of the bows by screws, as shown in Figs. 1 and 2. The lower ends, a^2 , of said straps are made solid, and have a hole formed in them longitudinally, upon the sides of which a screw-thread is cut.

C are the finger-irons, upon the upper ends

of which are formed screws, which screw into the screw-holes formed in the ends of the straps A, as shown in Fig. 2. Upon the lower ends of the inner fingers, c^1 , are formed eyes, by means of which they are pivoted to ears formed upon the sides of the outer fingers, c^2 , by rivets passing through said eyes and ears, as shown in Fig. 1. The outer fingers, c^2 , are made longer than the inner fingers, c^1 , and upon their lower ends are formed eyes, by means of which they are pivoted to each other and to the supporting-iron or seat rail D, as shown in Figs. 1 and 2.

The leather covers E are made and drawn upon the bows B after the straps A have been attached and before the fingers C have been secured into their places. The fingers C are then attached to the straps A, and the inner fingers, c^1 , securely pivoted to the outer fingers, c^2 , by the rivets c^3 . The outer fingers, c^2 , are then connected to each other and to the supporting-iron or seat-rail D, and secured in place by the nuts c^4 .

What I claim as new, and desire to secure by Letters Patent, is—

1. Attaching the bows to the hinge by screws, substantially in the manner herein shown and described, and for the purpose set forth.
2. The combination of the straps A and finger-irons C with each other, with the bows B, and with the supporting-iron or rail D, when the said straps and finger-irons are constructed substantially as herein shown and described, and for the purpose set forth.

GEO. W. TRAPHAGAN.
